(57) **CLAIM**

The ornamental design for a three dimensional frog shaped shoe, as shown and described.

DESCRIPTION

FIG. 1 is a perspective view of a three-dimensional frog shaped shoe, embodying my new design;

FIG. 2 is a side view thereof;

FIG. 3 is the other side view thereof;

FIG. 4 is a top view thereof;

FIG. 5 is a bottom view thereof;

FIG. 6 is a front view thereof; and,

FIG. 7 is a back view thereof.

The broken lines in the drawings represent unclaimed environmental subject matter.
